UNITED STATES PATENT OFFICE.

JAMES L. BARNES, OF FOSTORIA, OHIO.

WATER WHEEL.

Application filed August 15, 1922. Serial No. 582,007.

To all whom it may concern:

Be it known that I, JAMES L. BARNES, a citizen of the United States, residing at Fostoria, in the county of Seneca and State of 55 Ohio, have invented certain new and useful Improvements in Water Wheels, of which the following is a specification.

This invention relates to water wheels adapted both for over and under draft of the 10 water in which they may be completely submerged and in that position continue to run with very little loss of power, as the wings with which the wheels are provided are adapted to open when entering the current 15 and close when leaving the same. This feature makes a wheel of this character adaptable to almost any kind of river as it will work under all kinds of conditions of a river. It does not require a direct fall and eliminates the building of dams, although where 20 a direct fall is obtainable, this wheel can be used for under and over draft and will, in this manner, not only utilize the power as the water strikes the river bed, but may 25 equally well use it anywhere between the top and bottom of the fall. Moreover, the current above, as well as below the fall, may be utilized to drive the wheel.

Another advantage of this invention is 30 that it will also operate in streams where there is a strong under current, which may run in the same direction as the upper strata of the stream or in any other direction. As there may be several such currents, they can 35 be utilized to a great advantage on a wheel of this character, owing to the submersibility thereof. The power of the wheel depends upon its diameter and the size and number 40 of its buckets or wings as well as the structure of the frame.

One great advantage of this wheel resides in the fact that the erecting cost and installation thereof are very small; and another advantage of this wheel is its adaptability 45 to different types of streams for obtaining the desired power, in which case the use of a modified type of buckets and a suitable structure of the wheel frame will be necessary. 50 The frame or structure of this wheel can be standardized so that at any time additional wings or buckets may be furnished to obtain the power needed.

In the accompanying drawings one embodiment of the invention is illustrated, and 55

Fig. 1 shows a side elevation of the wheel in its simplest form and as used for light draft;

Fig. 2 is a top plan view and partial section of Figure 1, along line 2—2. 60

Fig. 3 is a perspective view of some of the details shown in Figs. 1 and 2;

Fig. 4 is a diagrammatic representation in side elevation of the structure of a large 65 wheel;

Fig. 5 is a side elevation of the bracket used for wheels requiring stronger construction;

Fig. 6 is a section along line 6—6 of Fig. 5;

Fig. 7 is a perspective view of one of the 70 supports or hinges for the wings;

Fig. 8 is a transverse section of a spoke with the wings unfolded;

Fig. 9 is a top plan view of a multiple 75 wheel, and

Fig. 10 is a perspective view of a radial arm with the wings unfolded.

The wheel in its simplest form as illustrated in Figs. 1, 2 and 3 comprises a hub 10 rigidly secured on a shaft 11 which is carried in suitable bearings 12 and provided with a pulley or gear wheel 13. The hub has a number of radial spokes 14 rigidly secured thereon and each spoke has a pair of wings 15 mounted in such a manner that they might fold inwardly to lie substantially in a vertical plane of the wheel and to unfold or open outwardly to lie substantially in a radial plane of the wheel. However, the wings do not unfold into a perfectly flat position but are preferably permitted to form an obtuse angle with relation to each other as seen in Figs. 8 and 10. Each wing is rigidly attached to two or more arms 37, revolvably mounted on the spoke 14, which carries, rigidly secured thereto, a bracket or abutment member 30. This member has a projecting abutment 34 for each of its adjacent wings as seen in Figure 3. For this purpose one abutment 34 extends to one side 80 of the bracket 30 and the other abutment to the opposite side thereof. In this manner the flat outer face of each arm 37 is adapted to lie on its corresponding abutment 34 when in unfolded position. These brackets may 85

be provided with additional abutments 33 90

100

105

for limiting the inward swinging of the wings into their folded position, as seen in Fig. 1, or each wing may contact with the inner bracket of a spoke behind it.

- 5 With the wheel partly submerged below the water line marked "W" as seen in Fig. 1, the action of the wings, will be as seen in that figure, that is to say, the wings to the left of the perpendicular line will all be unfolded, 10 while the lowermost wings on a rising spoke will commence to fold, and the remaining wings on the right hand side will be folded. In this manner the wings to the left, or in unfolded position, will set up a resistance 15 against the current of the water, so that the latter will impart a revolving action to the wheel, while when such action has ceased, the wings will fold and make very slight resistance, when lifted out of the water.
- 20 In case the wheel is entirely submerged, the same action on the wings will occur except that the wings on the descending side will remain folded a little longer or until nearing the horizontal position.
- 25 For greater power and larger wheels a stronger construction will be required, than what is shown in the first three figures just described and by referring to Figure 4 the construction for such a wheel will be understood. This construction is in the form 30 of a spider web having inner and outer sections bordered by radial spokes 20 which are preferably braced by means of transverse braces 21, in this manner dividing the wheel 35 into a hub section 22, an intermediary section 23 and an outer section 24. It will be evident that the number of sections may be multiplied as required.
- 30 The hub section 22 is formed in the same manner as already described with regard to Figs. 1, 2 and 3 and the outer sections are formed by extending the spokes to the outer periphery of the wheel and in the intermediary and outer sections are inserted radial 40 bars 25 secured on the braces 21 as seen in Fig. 4. On the spokes in each section are now secured in the same manner as has already been described, a pair of wings 26 and similar wings 27 are secured to the 45 radial bars 25. It will now be evident that every spoke and every radial bar will carry one or more pairs of wings, which are of a suitable width so as not to interfere with each other, when folding or unfolding.
- 50 In Figs. 5, 6, 7, 8 and 10 are shown details of a preferred construction for mounting the wings on the wheels, a similar construction having already been described in connection with Figure 3. In this case a 55 bracket 30 of segmental contour is rigidly secured on each spoke or bar 31. This bracket has segmental pockets or recesses 32 with radial side walls 33 and 34 adapted to abut respectively with the side of the wings 60 in folded and unfolded positions. As seen

in Figs. 5 and 6 these pockets 32 are provided one on each side of the bracket so that one of the pockets serves, for instance, to cooperate with the right hand wing while the other pocket serves to cooperate with the left hand wing, see Fig. 8.

In Fig. 7 is shown the type of hinge 37 preferably provided for a heavier constructed wheel. This hinge consists of a nave portion 35 embracing the spoke or radial arm so as to be able to swing around the same. At one side of the nave portion 35 extends a flat arm 36 to which the wing 15 is secured by means of rivets or bolts or in any other suitable manner. The wings are assembled, together with their hinges 37, in such a manner that the flat sides of the wings or hinges will contact with one of the radial walls 33 or 34 provided on the brackets 30 secured on the spokes or radial arms when in folded and unfolded position, respectively.

The framework or spider construction of the wheel consisting of spokes, braces and radial bars, is preferably built of metal tubing or solid metallic rods, or even of wood, and the wings may be constructed of sheet metal or wood and built in one piece or composed of a number of narrow strips or ribs. The hub of the wheel, as well as the 90 brackets and hinges, are preferably made of malleable cast iron or of steel.

In Fig. 9 is shown a construction of a wheel suitable for shallow streams or slow currents. In this case the diameter of the 100 wheel is limited and it is accordingly preferable to extend it in axial direction using a plurality of pairs of wings placed side by side.

Radial frames 40 are therefore provided having end spokes 41 connected by longitudinal bars 42 at their outer ends and by similar bars 43 near the main shaft 44. Hubs 45 for the outer spokes 41 are rigidly secured as at 46 on the main shaft 44. Intermediary spokes 47 extend between the inner and outer bars 43, 42 and wings 15 are mounted to oscillate on said spokes through the intermediary of hinges 37 and brackets 30, as already described. It is obvious that the length of the frames 40 and the number of wings carried in each frame is practically unlimited.

It will also be evident that instead of using long frames containing several spokes and as many pairs of wings, as illustrated in Fig. 9, a similar wheel may be built up of a plurality of wheel units illustrated in Fig. 2, assembled side by side on a common main shaft and that the scope of the claims is intended to cover both constructions.

Having thus described the invention, what is claimed as new is:

A water wheel comprising a hub, spokes radiating from the hub, pairs of wings hav-

ing hinge members engaged with the spokes, and segmental brackets secured upon the spokes between adjacent hinge members, said brackets being provided in their opposed 5 sides with pockets extending in opposite directions from the central radius of the bracket toward the side edge portions there-

of and each defining divergent walls projecting into the paths of the hinge members and adjacent portions of the wings to 10 limit the swinging movement of the wings.

In testimony whereof I affix my signature.

JAMES L. BARNES. [L. S.]
